CLAIM

The ornamental design for a case for mobile electronic device, as shown and described.

DESCRIPTION

FIG. 1 is a top front perspective view of a case for mobile electronic device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a bottom rear perspective view thereof.

The dashed broken lines in the figures depict portions of the case for mobile electronic device that form no part of the claimed design.

The grayscale in the drawings indicates a contrast of appearance.

1 Claim, 6 Drawing Sheets
